BRACKET

Charles I. Earll, York, Pa.

Application August 12, 1935, Serial No. 35,796

1 Claim. (Cl. 191—85)

My invention relates to brackets or holding mechanism for securing or attaching trolley retrievers, trolley catchers or similar equipment to the dash of vehicles such as street cars, trackless trolley coaches and the like.

The object of my invention is to provide a bracket which is adapted to be permanently secured to the dash of the vehicle and a case for the trolley retriever or trolley catcher, as the case 10 may be, adapted to contain the operating mechanism of such device and provide cooperating mechanisms between the bracket and the case by means of which the retriever or catcher, as the case may be, may be readily attached or detached from the bracket and when attached may be operated to rigidly hold the case in the bracket and to prevent vibration or rattle of the case in the bracket.

My invention consists in providing lugs on the 20 case or on the bracket and recesses on the bracket or the case adapted to co-act in the manner of the well known bayonet joint and in providing a cam adapted to operate between the bracket and a part of the case to take up the lost motion between the lugs and the recesses which they are 25 adapted to enter and between the bracket and the case to hold the case and bracket rigidly and to prevent any relative vibration or rattle.

In the drawing accompanying and forming part 30 of this specification Fig. 1 is a section on line 1—1 of Fig. 2. Fig. 2 is a front view of the bracket. Fig. 3 is a section on line 3—3 of Fig. 2. Figs. 4 and 5 are rear and side views respectively 35 of a part of the case which is received into and secured by the bracket. Figures 6, 7 and 8 are sections on lines 6—6, 7—7, and 8—8 of Figure 2.

The reference numerals are used in the same sense throughout the drawing and specification.

In the preferred embodiment of my invention 40 I provide a bracket, numeral 1, adapted to be bolted to the dash of the car. This bracket is provided with an annular flange 2 forming a recess adapted to receive the cylindrical portion 3 of the case and it is provided with the recesses 4 which are adapted to receive the lugs 14 on the case, in the well known manner of the bayonet joint.

These recesses or pockets 4 are each formed 50 with an opening 42 of sufficient size to admit lug 14 and a retaining wall or lips 43 behind which the lug may pass and be retained by it against forward movement, and they are arranged diametrically opposite each other and each has along its inner edge an annular rib 41 having a flat face.

55 At one side of the bracket midway between the

two recesses 4 I arrange a seat 5 and diametrically opposite it a seat 51 each extending a short distance either way from the line of the diameter and raised above the bottom of the recess. These seats and ribs 41 of the recesses or pockets have 5 their faces in the same plane and together afford four seats against which the rear face 6 of the case may rest.

A slot 52 is formed in flange 2 through which 10 extends a wedge shaped cam 7 carried by axial pin 8 which has its bearing in a lug 82 on the outside of flange 2. Handle 9 serves as means for rotating the cam on its axial pin. The cam is of gradually increasing thickness from its upper end 11 to its lower end 10.

In order to permit the cylindrical portion 3 of 15 the case to be inserted in the recess formed by flange 2 the handle 9 will be swung upward from the position in which it is shown in Figure 2 so that the cam will be out of the way. After the 20 cylindrical portion 3 has been inserted in the recess of the bracket and rotated to bring the lugs 14 in position back of lips 43 within the recesses 4 there will be a clearance between the back 6 of the case and seats 5 and 51. By turning handle 9 to 25 the position in which it is shown in Figure 2 cam 7 is forced through slot 52 into this clearance space to cause, by its wedging action, cylindrical portion 3 to move forward to force lugs 14 against 30 the walls of the recesses or pockets 4 with the result of holding the case rigidly against any movement relative to the bracket.

In order to hold the case in a central position 35 in the bracket and at the same time provide abundant clearance between the flange 2 of the exterior of the case which enters said flange I provide an annular opening 12 in the bracket which is adapted to receive the relatively small projection 13 on the back of the case.

It will be obvious that the same benefits may 40 be secured by mounting the cam 7 on the case and providing for its proper engagement with the bracket 1. The important feature of my invention being that means is provided for using unfinished castings for both the case and the bracket with abundant clearances for such unfinished castings and at the same time obtain a connection which is rigid and free from rattle. It has been found that not only is the noise of 45 the rattle objectionable in the modern quiet running street cars and more particularly on the trackless trolley coaches which run on rubber wheels but the continual vibration and oscillation of catchers and retrievers in their brackets as heretofore made causes excessive wear on the 50 55
